UNITED STATES PATENT OFFICE

VICTOR P. SCHMIDT AND HARRY A. BRENAMAN, OF ALTOONA, PENNSYLVANIA

MACHINE FOR GRINDING AXLES OR THE LIKE

Application filed June 9, 1931. Serial No. 543,046.

This invention relates to machines for grinding axles or the like and more particularly to portable grinding machines adapted to be affixed to and accurately centered on a cylindrical object to be ground, the invention being especially applicable to the grinding of journals or quills of locomotive axles. Heretofore it has been customary for the truing of locomotive or car axle journals to carry the axles to a lathe and to perform the work on the lathe, which, of course, involves considerable labor.

The primary object of this invention is to provide a comparatively simple and compact grinding machine which may be handily carried from place to place and which is adapted to be readily mounted for operation on the work to be ground, the machine being characterized by the use of a grinding tool which rotates about its own axis while revolving about the axis of the work.

Another object of the invention is to provide in a grinding machine of this character means for automatically advancing the tool operating mechanism longitudinally of the work as well as means for adjusting the vertical relation between the grinding tool and the work.

Other objects and advantages characteristic of our invention will become more fully apparent from the description hereinafter of one embodiment or example of the invention, the description having reference to the accompanying drawings, whereof:

Fig. I represents a side elevation of a grinding machine of our invention applied to a locomotive axle, certain parts being broken away for clearness in illustration.

Fig. II represents an end elevation of the same, as indicated by the lines II-II of Fig. I.

Fig. III represents an enlarged cross section of a portion of the collector ring of the grinding machine.

Fig. IV represents a perspective view of the annular bearing rings upon which the grinding machine is centered.

Fig. V represents a portion of the revolving carrier of the grinding machine showing

the part thereof to which the sliding block of Fig. VI is mounted; and,

Fig. VI represents a perspective view of fragments of the sliding block upon which parts of the grinding machine are mounted. 55

In the drawings a portion of a locomotive axle is represented at 1, and the particular area comprising the journal to be ground is represented at 2. Adjacent to this portion there is affixed rigidly to the axle around the body thereof an annular bearing in the form of split rings 3. As shown most clearly in Fig. IV, the rings 3 are made up of semi-circular segments assembled together by means of dovetailed joints 4. Each ring 3 is spaced from its companion ring by means of connecting bars 5 having flanged ends 6 which are bolted to plates 7 on the opposite sides of the ring segments by means of stud bolts 8. After the bearing rings 3 have been assembled together around the axle they are fixed on the axle by means of machine screws 9, which fit within correspondingly threaded openings disposed radially about the rings. To center the bearing rings 3 on the axle, we preferably employ a centering gauge such as the one described in our co-pending application for U. S. Letters Patent, Serial No. 543,047, filed June 9, 1931. 80 Although in the drawings, the portion of the axle to which the bearing rings are affixed is cylindrical, the rings may obviously be applied to shaft portions of a variety of cross-sectional shapes, as well as to tapering or irregular surfaces, and centered thereon. 85

On the annular bearing rings 3 there is mounted a revolvable carrier comprehensively designated at 10. The carrier 10 comprises two semi-circular sections 11 and 12 having 90 opposed flanges 13 and secured together by bolts 14. On one of the carrier sections 11 there is a projecting member 15, most clearly shown in Fig. V, which serves as a support for the grinding tool operating mechanism; whereas the other carrier section is provided with counterweights 16 for balancing the weight of the tool operating mechanism. The carrier 10 has inwardly projecting flanges 17 between which annular bush- 95 100

ings 18 are accommodated. The bushings 18 are in turn grooved to fit over the stationary rings 3. Accordingly, the carrier is concentric with and free to revolve about the annular bearing rings 3 which are fixed on the axle 1. Projecting laterally from one end of the carrier are a number of studs 19 which affords a means of attaching a split pulley 20 to the carrier. The studs 19 pass through holes in the inner ends of spokes 21 and are secured thereto by nuts 22.

In the present example of the invention, a pulley 20 serves as the driving element for the revolvable carrier 10, the pulley being connected by a belt with some convenient external source of power. However, it will be obvious that in lieu of a pulley and belt, many other forms of apparatus may be employed for transmitting rotary motion to the carrier 10.

The projecting support 15 on the carrier 10 is formed at its top surface with a central groove 23 and longitudinally extending keys 24. Upon this support a complementary shaped block 25, shown in perspective in Fig. VI, is slidably mounted, the block being restrained against vertical movement by means of the engagement of the keys 24 of the support 15 in the angular slots 26 of the block 25. Within a central threaded opening in the sliding block 25 a screw 27 is inserted. On the end of this screw there is a shoulder 28 which is engaged within a notch in a plate 29. The plate 29 is in turn screwed to a bracket 30, and the opposite end of the bracket 30 is secured to the carrier 10 by means of a pair of studs 31. On account of the engagement of the shoulder 28 of the screw 27 with the plate 29, which is fixed in relation to the carrier, the screw 27 cannot move in the direction of its length. Accordingly, when the screw 27 is turned, the sliding block 25 is caused to be moved along the supporting member 15 longitudinally of the work to be ground.

To turn the screw 27, and hence to advance the sliding block 25 with respect to the supporting member 15, a star wheel 32 is provided at the end of the screw. The star wheel 32 is actuated by a pin 33 which is fixed with relation to the axle 1, the pin 33 being carried on an arm 34 projecting outwardly from a split clamping ring 35. As shown in Figs. I and II, the sections of the clamping ring 35 are secured together at their flanged ends by bolts 36. The arm 34, which may be welded to the clamping ring 35, is provided with a threaded hole 37 and at opposite sides of the threaded hole 37 and equally spaced therefrom there are two larger openings 38 and 39. Within the threaded hole 37 a screw 40 is inserted with a spring 41 accommodated between the head of the screw and a disk 42. To the disk 42 the pin 33, previously

referred to, is attached. There is also a cap 43 on the disk 42, the cap housing the spring 41 and affording also a convenient part to be gripped with fingers, when changing the position of the pin 33 from the opening 38 to the opening 39 or vice versa.

When the pin 33 is in the position shown, that is, within the opening 38 in the arm 34, after each revolution of the carrier 10, the pin 33 will strike a tooth of the star wheel 32 above the center thereof and cause the star wheel 32 to turn in a counter-clockwise direction as viewed in Fig. II (assuming that the carrier is revolving in a clockwise direction). This will effect a turning of the screw 27 to advance the grinding tool operating mechanism in one direction longitudinally of the work. The position of the pin 33 may be changed from the opening 38 to the opening 39 by pulling the cap 43 outward against the pressure of the spring 41, and by turning the disk 42 to a position in which the pin 33 will spring into the opening 39 when the cap 43 is released. When the pin 33 is inserted within the opening 39, after each revolution of the carrier 10, the pin 33 will strike a tooth of the star wheel 32 below the center thereof and cause the star wheel 32 to turn in a clockwise direction as viewed in Fig. II (assuming that the carrier is revolving in a clockwise direction). This will effect a turning of the screw 27 to advance the grinding tool operating mechanism in the opposite direction. Accordingly, the position of the pin 33 controls the direction of longitudinal movement of the grinding tool operating mechanism.

On the sliding block 25 a motor carrying bracket 44 is mounted by means of studs 45 and nuts 46. An electric motor 47 of a conventional type is shown mounted on the bracket 44, the motor being movable in a vertical direction on the bracket 44 by means of a hand wheel 48. Attached to the motor shaft 49 is a grinding wheel 50 which is shown in engagement with the journal 2. By turning the hand wheel 48 in one direction or another, the vertical position of the grinding wheel may be adjusted in an obvious manner to regulate the engagement of the grinding wheel on the journal.

Associated with the pulley 20 there is a split collector ring 51, shown in Fig. III, which has a flange 62 secured to the spokes 21. The diameter of the collector ring 51 is slightly smaller than that of the pulley, and the two halves of the collector ring fit within the corresponding halves of the pulley 20. On the inside of the collector ring 51 there are two copper contact rings 52 which are in parallel spaced relation and are separated from the collector ring by suitable insulation 53. Lead wires 54 connect the copper contact rings 52 with the motor 47, there being

a sufficient length of such wire to allow for the necessary travel of the motor in a horizontal direction. Current from a suitable source is transmitted through conductors 55 to a stationary collector comprising contact shoes 56, shown in Fig. III. The shoes 56 are secured to a bracket 57 on the clamping ring 35 which in turn is affixed to the axle 1. At that end of the bracket 57 which projects in close proximity to the collector ring 51 there are two holes fitted with insulating bushings 58. Within these holes the cylindrical portions of the contact shoes 56 are inserted, and the conductors 55 are secured to the ends thereof by nuts 59 and insulating washers 60. Springs 61 serve to press the contact shoes into engagement with the copper rings 52 to maintain electrical contact between these parts while the carrier 10 revolves. Accordingly, current is transmitted through the stationary collector which forms the terminus of the conductors 55 to the revolving copper rings 52, and from thence is transmitted through the lead wires 54 to the motor 47.

It will be noted that the grinding machine of our invention may be applied to a locomotive axle by bringing the machine to the axle wherever it may be located. The various parts of the rotary grinding machine are assembled in a manner obvious from the above description. First, the bearing rings 3 are clamped at a convenient location on the axle and are accurately centered thereon. The carrier sections are then bolted together about the annular ring 3. With the carrier 10, the sections of the pulley 20 and collector ring 51 are joined together. Subsequently the clamping ring 35 and the various parts used for the support of the motor 47 and its electrical connections are assembled in their proper positions.

Assuming that the parts of the grinding machine occupy the position shown in Fig. I, the operation of the apparatus is as follows. The pulley 20 is belt-connected to a suitable source of power which causes the carrier 10 to revolve about the axis of the journal 2. The motor 47, having been properly adjusted to control the position of the grinding wheel 50, with relation to the journal 2, is operated to rotate the grinding wheel 50 about the axis of the motor shaft 49. As the carrier 10 completes each revolution, the pin 33 strikes the star wheel 32 causing the motor 47 with its grinding wheel 50 to be advanced a predetermined distance along the journal in the manner previously described. Accordingly, the grinding wheel 50 will eventually travel over the entire area of the journal 2. When the grinding wheel 50 reaches the end of its travel, the pin 33 is retracted from the opening 38 and is turned for insertion within the opening 39 of the arm 34 of the clamping ring 35. This effects

a reversal of the direction of travel of the grinding wheel 50. The operation is continued until the journal is ground to the desired depth.

It will be apparent that the machine herein described is of a compact nature and that it can be readily carried from place to place. Furthermore, the practice of the present invention eliminates the necessity of transporting locomotive axles to a lathe with obvious saving in the time and labor expended in truing the surface of a journal.

While we have described one example of a grinding machine of our invention, it will be apparent that various changes may be made in the form thereof without departing from the spirit of our invention as defined in the claims annexed hereto. It will be further apparent that the machine may be applied to many forms of shafts other than locomotive or car axles.

Having thus described our invention, we claim:

1. A machine for grinding axles or the like comprising an annular bearing adapted to be affixed rigidly to the work to be ground around the body thereof, said bearing being made up of separable segments, a carrier internally grooved to fit snugly on said annular bearing and adapted to be revolved thereon, a grinding tool adapted to engage the circumference of the work, and means for rotating said grinding tool about its axis.

2. A machine for grinding axles or the like comprising an annular bearing adapted to be affixed rigidly to the work to be ground around the body thereof, said bearing being in the form of split rings joined by spacing members, a carrier internally grooved to fit snugly on said rings and adapted to be revolved thereon, a grinding tool adapted to engage the circumference of the work, and means for rotating said grinding tool about its axis.

3. A machine for grinding axles or the like comprising an annular bearing adapted to be affixed rigidly to the work to be ground around the body thereof, a carrier revolvable on said bearing, a motor carrying bracket mounted on said carrier with capacity for movement longitudinally of the carrier and work, a motor mounted on said bracket, a grinding tool adapted to engage the circumference of the work and to be rotated by said motor, and means whereby each revolution of said carrier advances said motor carrying bracket a predetermined distance along the work.

4. A machine for grinding axles or the like comprising an annular bearing adapted to be affixed rigidly to the work to be ground around the body thereof, a carrier revolvable on said bearing, a block slidably mounted on said carrier with capacity for movement lon-

gitudinally of the work, a motor mounted on said sliding block, a grinding tool adapted to engage the circumference of the work, and to be rotated by said motor, a screw for advancing said sliding block on said carrier, said screw having a star wheel thereon, and means adapted to be mounted in fixed relation to the work and to engage said star wheel at each revolution of the carrier to turn
10 the screw aforesaid.

5. A machine for grinding axles or the like comprising an annular bearing adapted to be affixed rigidly to the work to be ground around the body thereof, a carrier revolvable on said bearing, a grinding tool adapted to engage the circumference of the work, and means for rotating said grinding wheel about its axis, said means being mounted on said carrier and having capacity for movement
15 longitudinally of the carrier and work as well as for adjustment in vertical relation to the carrier and work.

6. A machine for grinding axles or the like comprising an annular bearing adapted to be affixed rigidly to the work to be ground around the body thereof, a carrier revolvable on said bearing, a motor carrying bracket slidably mounted on said carrier with capacity for movement longitudinally of the work, a motor mounted on said bracket with capacity for vertical adjustment thereon, and a grinding tool adapted to engage the circumference of the work and to be rotated by said motor.

In testimony whereof, we have hereunto signed our names at Altoona, Pennsylvania, this 27th day of May, 1931.

VICTOR P. SCHMIDT.
